VACUUM CLEANER

Ferman C. Doughman, Stamford, Conn., assignor
to Electrolux Corporation, New York, N. Y., a
corporation of Delaware

Application July 23, 1941, Serial No. 403,625

4 Claims. (Cl. 230—117)

This invention relates to vacuum cleaners and particularly to vacuum cleaners of the so-called inside bag type having a dust separator and a motor-fan unit located in a cleaner housing.

In the operation of vacuum cleaners some noise is produced by the flow of air through the cleaner and additional noise is caused by vibration of the motor-fan unit in its operation. Vibration of the motor-fan unit may be transmitted to other parts of the vacuum cleaner, increasing any noise produced thereby and possibly loosening parts of the cleaner.

The objects of the present invention are to provide an improved motor-fan unit mounting for reducing the noise and vibration produced by the operation of said unit, and to so construct the motor-fan unit and its mounting that it may be readily removed and replaced in the vacuum cleaner housing without special skill or tools.

The various features and advantages of the invention may be better understood by reference to the following specification and appended claims when considered in connection with the accompanying drawing, in which:

Fig. 1 is a longitudinal sectional view of a vacuum cleaner embodying the invention; and

Fig. 2 is an enlarged sectional view through the motor-fan compartment of the vacuum cleaner, showing the construction and mounting of the motor-fan unit.

Fig. 3 is a fragmentary vertical sectional view taken somewhat to one side of the section of Fig. 2 showing a method of assembly of the parts therein shown, and also the position of the air holes in the rear supporting plate.

The vacuum cleaner, in the form shown in the drawing, includes a cylindrical housing 10 having a transverse interior bulkhead 11 which divides the housing into a dust compartment 12 and a motor-fan compartment 13.

The forward end of the vacuum cleaner is provided with a cover 14 which is detachably secured thereto by means of suitable clamps 15, providing access to the dust bag 16 within the dust compartment 12. Cover 14 is provided with a suitable coupling member 17 for attachment to a flexible hose 18, by which the cleaner may be pulled by the operator. Hose 18 is attached to a hollow wand 19 to which is connected the nozzle 20.

The cleaner unit rests on runners 22 by means of which it may be pulled over the floor or carpet. This general type of cleaner and its mode of use are well known. The operator generally holds the wand 19 with the flexible hose 18

loose between the cleaner unit and the wand. The upper portion of housing 10 is provided with a ridge 23. An elongated handle 24 of rubber or other suitable material is secured to the ridge 23 and to the top of housing 10 adjacent the rear end thereof, the handle forming in effect a continuation of the ridge 23. The handle is above the motor-fan compartment which is at the center of gravity of the cleaner unit.

The bulkhead 11 which, as previously described, separates the dust compartment 12 from the motor-fan compartment 13, has an outer cylindrical flange 26 which is preferably welded to the inner wall of housing 10 as shown in Fig. 2. The bulkhead 11 has a central opening 27 surrounded by a flange or collar 28, the said opening 27 providing the only passage for air between dust compartment 12 and motor-fan compartment 13. Tabs 29 project inwardly from the peripheral edge of the opening 27 in bulkhead 11 and serve as stops for a screen 30 which is secured to the bulkhead 11 within dust compartment 12 as shown in Fig. 2. A suitable filter pad 31 may be secured to the bulkhead between dust bag 16 and screen 30. The dust bag is preferably large so as to wrinkle within chamber 12 and distention of the dust bag is resisted by screen 30 and tabs 29.

The motor-fan unit is constructed as a single entity and is adapted to be readily inserted into the compartment 13 and withdrawn therefrom as a unit without requiring assembly or adjustment of any kind. This unit includes a fan casing 33 and a motor casing 34 which are secured together in a unitary structure, the parts for example being welded at 35 and bolted at 36.

The fan casing 33 comprises two fan housings 38 and 39. Housing 39 extends between centrifugal fans 40 and 41 which are mounted on the armature shaft 42 of motor 43 which is preferably of the series wound type. Intermediate directing vanes 44 are mounted on housing 39 as best shown in Fig. 2.

The fan casing 33 has an opening surrounded by a cylindrical metal flange or collar 46 which is disposed axially of the armature shaft 42 of motor 43. Secured to flange 46 is a resilient vibration-absorbing ring or collar 47 consisting of inner and outer annular metal bands 48 and 49 between which a resilient annular band 50 is secured by vulcanizing or in any other suitable manner. The resilient band 50 is preferably made of rubber and, in the form illustrated, has arcuate slots 51 formed in the face thereof to increase its resiliency. The resilient ring or collar

47 which is thus secured to the flange 46 of fan casing 33 is adapted to fit snugly within the annular flange 28 of bulkhead 11 to support the forward end of the motor-fan unit within the compartment 13 of vacuum cleaner housing 10 when the cleaner is assembled as hereinafter described, the outer metal band 49 of ring 47 being readily slidable into and out of said flange 28.

Motor casing 34 is formed at its rear end with a circular hub 53 to which there is removably attached a resilient vibration-absorbing ring or collar 54 similar to the ring 47 described above. This ring assembly consists of inner and outer metal bands 55 and 56 and a band 57 of rubber or similar resilient material which is located between and vulcanized or otherwise secured to the bands 55 and 56, the band 57 likewise preferably having arcuate slots 58 formed in its face to increase the resiliency of the ring assembly 54.

The motor casing has a rear supporting plate 60 having an annular inwardly-turned flange 61 which fits snugly over the outer metal band 56 of the vibration-absorbing ring 54. As illustrated the flange 61 is riveted to the plate 60, but it may be secured thereto in any other manner or may be formed integral therewith. The plate 60 extends radially inwardly beyond flange 61 a distance substantially equal to the thickness of band 56 and the flange 61 has its inner edge spun over at 62, thus securely fixing the band 56, and consequently, the entire ring assembly 54 to the plate 60. A lock wire 63 is sprung upon the hub 53 of the motor casing to removably lock the assembly 54 thereto. The inner metal band 55 facilitates removal of ring 54 from the hub 53 after the motor-fan unit and plate 60 are withdrawn from the housing.

The rear supporting plate 60 is thus secured to the motor casing through the intermediary of the vibration-absorbing ring 54, thus isolating vibrations of the motor-fan unit from the plate 60 and from the vacuum cleaner casing 10. The plate 60 is secured to filter casing 65 in any suitable manner, by welding for example, as indicated at 74. The casing 65 is detachably secured to the cleaner casing 10 by any suitable means. In Fig. 3, by way of example, the parts are shown bolted together. Also shown in this figure are air holes 75 in plate 60. Filter compartment casing 65 has a discharge opening 66. A filter may be placed in compartment casing 65 in addition to or in lieu of filter pad 31. Attached to casing 65 are the usual step switch 69, plug 70 and the various electrical connections to the motor. The rear of the vacuum cleaner housing 10 is closed by means of a cover 71 which may be detachably secured thereto in any suitable manner as by means of a screw 72, the cover 71 having an opening 73 registering with opening 66 in filter casing 65. Cover 71 also has a suitable opening to permit the step switch 69 to project therefrom, and an opening providing access to the plug 70.

The motor-fan unit including fan casing 33 and motor casing 34 is a single unitary structure, as previously described, and the special mounting described above enables said unit to be removed from the motor-fan compartment 13 of vacuum cleaner casing 10, and reinserted therein, with a minimum of effort and without requiring special skill or tools. In assembling the parts, all that is necessary is to insert the forward end of fan casing 33 into the rear open end of compartment 13 until the resilient ring 47 telescopes

into the flange 28 of bulkhead 11, after which the filter casing 65 and supporting plate 60 are simply bolted to the interior of cylindrical housing 10, as shown in Fig. 3 and the rear cover 71 is secured in place. When so assembled, the resilient vibration-absorbing rings 47 and 54 constitute the sole support for the motor-fan unit within the vacuum cleaner housing 10.

In operation, the motor 43 and fans 40 and 41 are rotated and produce a flow of air from left to right in the cleaner housing 10, as viewed in the drawing, thus producing a suction at the cleaning nozzle 20. When the nozzle 20 is in contact with a rug, a certain amount of air and dirt will be drawn into the vacuum cleaner bag. When nozzle 20 is lifted from the rug, a greater quantity of air will flow through the cleaner, which will increase the load on the motor and fans and thus, with a variable speed motor, result in reducing the speed of rotation. If the nozzle 20 is sealed tight against an impervious surface there may be substantially no flow of air through the vacuum cleaner, and in such case the load on the motor and fans will be reduced and result in an increase in speed of rotation.

The motor 43 being of the series wound type produces a torque in the armature which increases as the load increases and causes a decrease in the speed of rotation of the armature. As the cleaning tool or nozzle 20 traverses various surfaces which are being cleaned, the quantity of air flowing therethrough may vary over a wide range. The resulting variation in the reactive torque is absorbed by the resilient rings 47 and 54 without producing sympathetic vibrations in other parts of the vacuum cleaner. Due to the construction of the resilient rings 47 and 54, and due to the fact that said rings are located axially of the armature shaft of the motor and at a relatively small radius from the axis of the motor, they will absorb the greater part of the vibrations and prevent them from being transmitted, thus substantially reducing the noise of operation as well as the possibility of loosening the parts of the machine.

The invention claimed is:

1. A vacuum cleaner comprising a housing having an opening at each end, a transverse bulkhead within said housing having a central flanged opening therein and dividing the housing into a dust compartment at the forward end and a motor-fan compartment at the rear end of the housing, a motor-fan unit adapted for insertion in said last-mentioned compartment through the opening at the rear end of said housing, a short tubular member projecting outwardly from the forward end of said unit and being of substantially less diameter than said unit and constituting an inlet passage for the fan, a resilient ring permanently secured around said tubular member and adapted to slide into the flanged opening in said bulkhead to support said unit therein, a second resilient ring on the rear end of said motor-fan unit, and means for supporting said second ring in said housing.

2. A vacuum cleaner comprising a housing having an opening at each end, a transverse bulkhead within said housing having a central opening therein and dividing the housing into a dust compartment at the forward end and a motor-fan compartment at the rear end of the housing, a motor-fan unit adapted for insertion in said last-mentioned compartment through the rear end of said housing, a resilient ring per-

manently secured on the forward end of said motor-fan unit, an outer metal band secured around said ring and providing a metal surface slidable into the opening in said bulkhead to support said unit thereon, a second resilient ring on the rear end of said motor-fan unit, a rear plate secured to said second resilient ring, and means for securing said rear plate to said housing.

3. A vacuum cleaner comprising a housing having an opening at each end, a transverse bulkhead within said housing having a central flanged opening therein and dividing the housing into a dust compartment at the forward end and a motor-fan compartment at the rear end of the housing, a motor-fan unit adapted for insertion in said last-mentioned compartment through the opening at the rear end of said housing, a short tubular member projecting outwardly from the forward end of said unit and being of substantially less diameter than said unit and constituting an inlet passage for the fan, a resilient ring permanently secured around said tubular member, an outer metal band secured around said ring and providing a metal surface slidable into the flanged opening in said bulkhead

to support said unit therein, a second resilient ring on the rear end of said motor-fan unit, and means for supporting said second ring in said housing.

5. 4. A vacuum cleaner comprising a housing having an opening at each end, a transverse bulkhead within said housing having a central opening therein and dividing the housing into a dust compartment and a motor-fan compartment, a motor-fan unit in said housing including a motor having an armature shaft and a rotary fan carried thereby, a resilient ring permanently secured to one end of said motor-fan unit around the axis of said armature, said ring having an outer metal band secured thereto and providing a metal surface slidable into the opening in said bulkhead to support said unit thereon, a second resilient ring secured to the other end of said motor-fan unit around the axis of said armature, a rear plate secured to said second resilient ring and removable with said motor-fan unit, and means for detachably securing said rear plate to said housing permitting the removal of said motor-fan unit upon releasing said rear plate.
